FLOW DEVICE

Rey A. Lamb and William H. Waring, Dallas,
Tex., assignors to Merla Tool Corporation, Dallas, Tex., a corporation of Texas

Application February 4, 1939, Serial No. 254,558

15 Claims. (Cl. 103—232)

This invention relates to new and useful improvements in flow devices.

One object of the invention is to provide an improved device for controlling the admission of a lifting fluid, such as gas or air, into a liquid column whereby said column is lifted or raised by said fluid, the device being particularly adapted for use in oil wells to lift the well liquids to the surface.

An important object of the invention is to provide an improved flow device which is arranged to be run into and removed from the well bore by means of a flexible element, such as a wire line or cable, whereby insertion and removal thereof is possible without pulling the tubing, as is the usual practice.

Another object of the invention is to provide an improved well flow apparatus which includes a seating member connected in the tubing string at a desired elevation therein, together with a valve assembly arranged to be run into and removed from the tubing on a wire line and adapted to be removably supported in the seating member; the valve assembly being constructed so as to control the flow of a pressure lifting fluid into the well liquid column standing in the well casing, whereby said column is lifted to the surface by said pressure fluid.

A particular object of the invention is to provide an improved flow device which is arranged to be removably seated in the well tubing and which controls the flow of a lifting gas from said tubing into the well liquid in the well casing, said device being actuated by a predetermined pressure differential between the liquid in the casing and the gas in the tubing and being constructed to admit a charge of gas and then completely shut off, whereby the device is particularly adapted for use as an intermitter and may be successfully employed in wells having a relatively low standing level.

A further object of the invention is to provide an improved device, of the character described, wherein the valve assembly is adapted to be removably seated within a supporting member, together with improved pressure seal packing means for sealing off between the assembly and member so as to prevent leakage of pressure past these parts.

Still another object of the invention is to provide an improved flow device, of the character described, wherein the valve element is provided with longitudinal flutes or grooves which conduct the lifting gas past the element to the gas inlet opening, said flutes being associated with the cyl-

inders in which the element is movable and being tapered or gradually reduced so that as the element moves toward its closed position, the reduced ends of the flutes approach the cylinder wall to cause the element to act with a piston effect since the cross-sectional area of the element is, in effect, exposed to the pressure moving the element to a closed position; such piston effect assuring the positive shutting or closing of the gas inlet after each charge of gas is admitted.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view, partly in section and partly in elevation, illustrating a flow device, constructed in accordance with the invention, mounted within the well tubing.

Figure 2 is an enlarged, transverse, sectional view of the valve assembly with the valve element in position prior to movement.

Figure 3 is a view, similar to Figure 2, with the valve element in intermediate position.

Figure 4 is a view similar to Figure 3, with the valve in shut-off position.

Figure 5 is a horizontal, cross-sectional view, taken on the line 5—5 of Figure 2.

Figure 6 is a horizontal, cross-sectional view, taken on the line 6—6 of Figure 2, and

Figure 7 is an enlarged detail, illustrating the engagement of the valve with the seat.

In the drawings, the numeral 10 designates a well casing which extends throughout the length of the well bore in the usual manner. The lower end of the casing is open and the well liquid from the producing area enters said casing and rises to a level therein, which level varies with the particular conditions of the well. The well tubing 11 extends axially through the well casing and has its lower end open whereby communication between the interior or bore of said tubing and the bore of the casing is established. A flow device A is arranged to be mounted within the well tubing and is preferably located below the normal standing liquid level thereof. As will be explained, the device is removably supported in the tubing and controls the admittance of a lifting medium, such as gas or air, from the tubing into the liquid column in the casing. The lifting medium is introduced into the upper end of the tubing and must flow downwardly through the de-

vice A in order to escape from the lower end of the tubing into the well casing 10.

The flow device A is particularly adapted to intermittently admit gas, as needed, to the liquid column to raise the same to the surface and may be termed an intermitter. The conditions of the well may be such that a period of time is required for the well liquid to build up to a normal standing level in the casing and the device A is arranged to be actuated by the differential in pressures between the gas in the tubing 11 and the liquid in the casing, as will be hereinafter explained, whereby a predetermined liquid level is necessary before gas is admitted to the liquid column to raise the same. After the liquid column is raised, the device A automatically shuts off the gas flowing into the casing through said device and the liquid level must again build up in said casing before gas is admitted thereto. Since the device A may be supported within the tubing at any desired elevation, it will be obvious that it may be readily employed in wells having a relatively low standing liquid level.

As has been stated, the flow device A is arranged to be removably supported in the well tubing 11 and in carrying out the invention, an elongate supporting sleeve or nipple 12 is connected in the tubing. The sleeve has its ends externally screw-threaded to facilitate its connection in the tubing and said sleeve is located at any desired elevation, being preferably below the normal standing liquid level, indicated at L in Figure 1. An internal, annular shoulder 13 is formed within the bore of the sleeve near its lower end and the wall of the bore is bevelled immediately above said shoulder, as shown at 13'. The annular bevel 13' and shoulder 13 form a seating surface for supporting the flow device A within the bore of the tubing.

The flow device A includes an elongate cylinder 15 which is constructed of an upper section 15a and a lower section 15b, which sections have screw-threaded connection. The lower section 15b is formed with a reduced, externally screw-threaded collar 16 which receives the upper end of a tubular mandrel 17. The external diameter of the upper portion of the mandrel is substantially equal to, or slightly less than, the diameter of the bore 14 of the supporting sleeve 12 so as to have a sliding fit therein (Figure 2), while the lower portion of the mandrel is reduced to provide a tubular shank 17', on which a plurality of inverted packing cups are mounted. The cups are constructed of an elastic packing material, and are spaced from each other by a spacer ring 19, the ring and cups being retained on the shank by an annular retaining collar 20 which is screw-threaded onto the lower end of the shank.

The collar 20 has a sliding fit within the bore 14 of the supporting sleeve 12 and the lower end of said collar is bevelled complementary to the bevel 13' above the shoulder 13. The lower edge of the collar is adapted to rest on the shoulder 13 with its bevelled portion engaging the bevel 13' within the bore 14 and in this manner, the mandrel 17 and cylinder 15 are supported in the well tubing. When so supported, the outer surfaces of the inverted packing cups 18 engage the wall of the bore 14 of the supporting sleeve and, manifestly, any pressure in the bore of the tubing above said cups acts on said cups to distort the same radially outwardly, whereby sealing off between the mandrel 17 and the sleeve 12 is assured. Therefore, when the collar 20 is seated and the cylinder 15 and mandrel 17 are supported

within the tubing, the well liquid in the tubing below the mandrel cannot flow upwardly between the mandrel and supporting sleeve; also, the lifting medium in the tubing above the mandrel cannot by-pass said mandrel and, therefore, the only communication between the bore of the tubing above the device A and the bore of the tubing below said device must be through the bore of the cylinder 15 and through the tubular mandrel. It is pointed out that the pressure above the cups not only distorts the same into sealing position, but also holds the assembly downwardly on the seat 13 to prevent upward displacement thereof by pressure from below.

15 The upper section 15a of the cylinder 15 is formed with an axial bore 21 which has its lower portion reduced at 21a to form an internal, annular shoulder 22. The upper end of the bore is provided with internal screw threads which are arranged to receive the lower portion of a tubular fishing neck 23. The upper end of the fishing neck is formed with the usual undercut shoulder 24, whereby a suitable tool (not shown) may be engaged therewith to permit lowering and raising of the device A on a wire line or cable. Manifestly, when a flexible element is employed to raise and lower the device A, the same may be quickly inserted or removed from the tubing without disturbing said tubing, whereby the labor and time required for inserting and removing the device is minimized. The lower portion of the fishing neck 23 extends into the bore 21 of the cylinder and the lower edge of said neck is bevelled to provide an annular seat 25.

30 25 The lower end of the upper section 15a of the cylinder engages within the bore 26 of the lower section 15b. The lower portion of the bore is reduced to provide an internal, annular shoulder 27 and the inner peripheral portion of this shoulder is bevelled to provide a valve seat 28. Below the valve seat the bore 26 is slightly enlarged so as to have a diameter substantially equal to the diameter of the bore of the mandrel 17 which is connected to the lower end of the cylinder 15. 35 From the foregoing, it will be obvious that a lifting gas introduced into the upper end of the tubing 11 may flow downwardly through said tubing and then through the tubular fishing neck, through the cylinder and finally through the tubular mandrel 17. This gas may then pass downwardly through the remainder of the tubing below the device A and from the lower end thereof into the well casing 10 to lift the well liquid upwardly through the well casing to the surface.

55 45 For controlling the flow of the lifting gas through the bore of the cylinder 21 and thereby controlling the admittance of the lifting gas to the liquid column, an elongate plunger or piston 30 is slidably mounted within the cylinder 21. The plunger has a sliding fit within the reduced portion 21a of the cylinder bore and its upper end projects into the upper portion of said bore. The extreme upper end of the plunger has an enlarged, conical head 31 preferably integral therewith and the head is adapted to engage the annular seat 25 formed at the lower edge of the fishing neck 23. When seated, the head closes the bore of the cylinder to prevent flow therethrough. A coiled spring 32 surrounds the upper portion of the plunger, being confined between the head and the internal shoulder 22 within the bore, and said spring exerts its pressure to constantly urge the plunger upwardly so as to urge the head 31 toward its seat 25.

The lower end of the plunger is provided with a depending metering element or pin 33 which is preferably integral therewith and projects axially therefrom. The outer surface or contour of the pin is subject to variation but it has been found preferable to make the same along the lines of a logarithmic curve, whereby the pin is curved or tapered inwardly, the diameter thereof gradually reducing to an axial point or extremity. An external, annular shoulder 34 is formed immediately above the pin 33 at the lower end of the plunger or piston 30 and when the plunger moves downwardly in the cylinder 15 (Figure 4), this shoulder is arranged to engage the bevelled seat 28 which is located within the lower section 15b of the cylinder. Manifestly, when the shoulder 34 engages the seat 28, further downward movement of the plunger is arrested and flow past the seat is completely shut off. It is noted that the bevel or incline of the seat 28 is different from and is not complementary to the bevel or incline of the shoulder 34, whereby the shoulder engages the seat at one point only. This point contact reduces the possibility of foreign matter which might accumulate on the seat interfering with the positive seating of the shoulder, and also causes the entire cross-sectional area of the plunger to be exposed to the pressures acting thereon (Figures 4 and 7).

Above the external shoulder 34 at the lower end of the plunger, the outer surface of said plunger is formed with a plurality of vertically extending flutes or channels 35 which are spaced around the lower portion of the plunger. The lower ends of the flutes terminate short of the shoulder 34, whereby a portion 34a of the outer surface of the plunger is disposed between the ends of the flutes and said shoulder. When the plunger 30 is in its uppermost position (Figures 1 and 2) with the conical head 31 in a seated position, the lower ends of the flutes or channels are within the reduced portion 21a of the bore of the cylinder, while the upper ends of the flutes are above the internal shoulder 22, being exposed to the interior of the enlarged upper portion of the cylinder bore 21. Manifestly, at this time, the lifting gas above the plunger cannot enter the bore of the cylinder since the head 31 is seated.

The upper end of each flute or groove 35 is gradually reduced as shown at 35' and the length of the flutes is such that when the plunger moves to its lowermost position (Figure 4) with the shoulder 34 engaging the seat 28, the upper ends of said flutes are within the reduced portion 21a of the cylinder bore. Therefore, when the plunger is in a lowermost position, the lifting gas cannot flow past the plunger. It is pointed out that the flutes or grooves 35 provide by-pass channels to allow the lifting gas to flow downwardly past the plunger 30. When the plunger is first moved downwardly to unseat the head 31, the gas enters the bore 21 of the cylinder and flows downwardly through the flutes and then through the bore 26 of the lower cylinder section 15b to the tubing therebelow. The head 31 is formed with vertical grooves or passages 31a. As the plunger continues its downward movement, the metering pin 33 enters the reduced portion of the bore 26 below the seat 28 and metering of the flow past the seat begins. At the same time, the reduced upper portions 35' of the flutes 35 move toward the shoulder 22 to gradually reduce the by-pass opening for the

gas flowing past the plunger and, therefore, a double metering action is obtained. The reduction of the upper end of the flutes may be comparable to the gradual reduction of the surface of the metering pin, that is along the lines of a logarithmic curve, so that the metering action of both these elements will be the same. However, the invention is not to be limited to the flutes and pin producing exactly the same metering action as good results may be obtained without such relation between these parts. As explained, the upper ends of the flutes 35 enter the reduced portion 21a of the cylinder bore 21 when the shoulder 34 engages the seat 28, whereby a double shut-off is provided. Of course, it would be possible to make the flutes slightly longer, in which event, the gas could continue to by-pass the plunger and enter the bore 26 above the seat 28 after the shoulder 34 has seated. This gas, however, could not flow past said seat since the engagement of the shoulder 34 therewith would prevent such occurrence.

The supporting sleeve or nipple 12 is connected at the desired elevation in the tubing string 11 and is lowered into the well casing 10 with the tubing. At this time, the valve assembly A is not located within the sleeve 12. After the tubing has been set within the well casing, a suitable tool (not shown) is engaged with the fishing neck 23 and the valve assembly is lowered through the well tubing. Of course, at this time there is no gas pressure within the tubing. The valve assembly is lowered through the tubing until the collar 20 and mandrel 17 at the lower end of said assembly enter the bore 14 of the supporting sleeve 12 and lowering continues until the lower end of the collar is seated on the internal shoulder 13 within said sleeve. The lowering tool (not shown) is then disengaged from the fishing neck 23 and is removed from the tubing, leaving the valve assembly supported within the bore of said tubing.

During the lowering of the valve assembly into its proper position, the valve plunger 30 is in the position shown in Figure 2, being held in such position by the coiled spring 32 which holds the conical head 31 in engagement with the seat 25. The auxiliary lifting fluid, such as gas or air, is then introduced into the upper end of the well tubing 11 and flows downwardly therethrough. For purposes of this description, it will be assumed that the lifting medium is gas and said gas is built up to a desired pressure, which pressure is dependent upon the conditions of the particular well.

The gas pressure within the tubing acts against the upper end of the plunger 30 and when such pressure reaches a predetermined point, sufficient to overcome the pressure of the spring 32 and the pressure within the bore of the tubing below the valve assembly, then the plunger is moved to its lowermost position, with the annular shoulder 34 engaging the seat 28 within the lower end of the cylinder (Figure 4). In this position, the bore of the cylinder 15 is closed and the gas in the tubing 11 above the valve plunger cannot flow downwardly into the tubing below said plunger with the result that said gas cannot enter the liquid column in the well casing. At this time, the coiled spring 32 is under tension and is exerting its force upwardly against the gas pressure which is acting on the upper end of the plunger 30. The lower end of the pin 33 is exposed to the pressure of the well liquid which is in the well casing and which is also in the tubing below the valve assem-

bly and this pressure is urging the plunger upwardly. Therefore, it will be seen that the well liquid pressure plus the force of the compressed spring is urging the plunger toward a raised position, which movement is resisted by the gas pressure in the tubing acting against the upper end of said plunger.

As the liquid column in the well casing 10 and also in the lower portion of the well tubing 11 continues building up to rise toward a normal standing liquid level, the pressure within the tubing which is acting against the lower end of the metering pin 33, is increased. When this pressure reaches a predetermined point, as determined by the size of the spring 32 and the gas pressure in the upper portion of the tubing, the plunger is moved upwardly against the pressure of the gas, whereby the metering pin 33 is moved upwardly with relation to the reduced portion of the cylinder bore. Such movement of the plunger unseats the shoulder 34 and moves it away from its seat 28, whereby a flow past said seat may occur. At the same time that the upper portion of the pin 33 moves upwardly out of the reduced portion of the bore, the extreme upper ends of the flutes or channels 35 in the plunger move upwardly and out of the reduced portion 21a of the bore of the upper section 15a of the cylinder. When this occurs, the lifting gas in the tubing 11 above the valve assembly may flow downwardly through the vertical flutes or channels 35 and into the bore 26 of the lower section 15b of the cylinder. This gas may then flow downwardly through the mandrel 17 and into the tubing below the valve assembly. This admitted gas forces the liquid from the lower end of the tubing and upwardly in the well casing 10, said gas following the liquid and escaping upwardly through the well casing. Of course, the charge of admitted gas will naturally lift the fluid through the casing 10 to the surface.

As soon as upward movement of the column of liquid in the casing 10 begins, the pressure which has been acting against the underside or lower end of the plunger 30 is reduced. The upper end of the plunger is exposed to the gas pressure which is constant and, therefore, the reduction of the pressure below the plunger causes said plunger to again move downwardly. Such downward movement of the plunger moves the lower reduced end of the metering pin 33 into the reduced portion of the bore 26, and as said pin enters the opening, the cross-sectional flow area of the bore is gradually reduced. This gradual reduction increases the velocity of the gas passing around the pin 33 through said bore and, at the same time, a greater cross-sectional pin area is moving into the bore. The increased velocity of the gas flowing through the bore further reduces the pressure below the pin and, also, the pin entering the bore acts with the same effect as a piston within a cylinder, whereby the rate of movement of the plunger is increased as it moves downwardly. The plunger continues its downward movement until the shoulder 34 engages the seat 28.

The contour or curvature of the pin is a controlling factor as to the rate or speed of downward movement of the plunger. As shown in the drawings, the curved taper is more or less gradual and therefore as the pin moves into the bore, the reduction of flow area around the pin is relatively gradual and the rate of increase in speed of movement of the plunger is gradual. If the pin was made with a longer taper, the reduction of

flow area and the speed of movement of the pin would be decreased with the result that it would require a longer time for the shoulder 34 to engage the seat and, thus, more gas would enter the tubing below the valve assembly upon each actuation of the plunger. Similarly, if the contour of the pin were more rounded, the reduction of flow area of the bore would be more abrupt and thereby result in a more rapid downward movement of the plunger. Thus, it will be apparent that by varying the contour of the pin, the time required for the plunger to complete its downward movement may be controlled, whereby the volume of gas in each charge admitted may be accurately controlled.

As the plunger 30 moves downwardly and the metering pin 33 enters the bore to reduce the flow area around said pin, the upper ends of the flutes or channels 35 also move downwardly with relation to the reduced portion 21a of the cylinder bore. As has been explained, the upper ends of these flutes are gradually reduced and, obviously, as the plunger moves downwardly within the reduced portion 21a of the cylinder bore, the flutes act to cut down the flow area or the size of the opening through which the gas from above may flow. By controlling or varying the curvature and taper of the upper ends of the flutes, it is possible to accurately meter the flow of gas through the channels in accordance with the movement of the plunger. Thus, it will be seen that by forming the flutes in the manner shown, it is possible to obtain substantially the same metering action with the flutes, as is obtained by the curved metering pin 33 entering the reduced portion of the bore 26. The length of the flutes 35 is such that when the shoulder 34 engages its seat 28 the upper ends of said flutes are within the reduced portion 21a of the cylinder bore and, therefore, the gas from above the plunger is completely shut off and cannot flow through said flutes. It may be desirable in some instances to arrange the flutes so that their upper ends enter the reduced portion 21a of the cylinder bore just prior to the engagement of the shoulder 34 with its seat 28. With this arrangement, the gas within the bore 26 around the pin 33 can flow downwardly through the mandrel 17 and this will further lower the pressure below the plunger, whereby the constant gas pressure above the plunger will positively move the shoulder into engagement with its seat. This will assure a positive and complete shutting off of the gas supply to the liquid column.

After the plunger 30 is seated to close the cylinder bore (Figure 4), the parts remain in this position until the pressure of the well liquid again builds up to the predetermined point necessary to unseat the plunger upwardly. The size and force of the spring 32 aid in controlling the pressure differential and said spring may be varied to take care of the various well conditions. Obviously, the device operates to admit a charge of gas to raise the well liquid and after the charge is admitted the device positively shuts off the gas until the same is again needed. This makes the valve particularly adapted for use as an intermitter for flowing wells having a relatively low standing liquid level.

In the event that the valve plunger should need replacing or in the event that the spring 32 must be changed due to a change in well conditions, it is only necessary to lower a fishing tool (not shown) and engage the same with the fishing neck 23. The entire valve assembly may then

be removed from the well tubing without disturbing said tubing. Removal or insertion of the device may be on a wire line or cable and may be accomplished in a minimum length of time and with a minimum amount of labor.

The foregoing description of the invention is explanatory thereof and various changes in the size, shape and materials, as well as in the details of the illustrated construction may be made, within the scope of the appended claims, without departing from the spirit of the invention.

What we claim and desire to secure by Letters Patent is:

1. A well flowing apparatus including, a well casing having a well liquid inlet, a well tubing extending through the well casing and having its lower portion communicating with the bore of the casing, a support connected in the tubing string, a flow valve assembly arranged to be run into and removed from the well tubing and adapted to be removably supported on said support, and means for introducing a pressure lifting gas into the upper end of the tubing so that the same flows downwardly therein, the valve assembly including a valve plunger located in the line of flow through the tubing for controlling the admittance of said gas to the liquid in the casing and having one end exposed to the gas in the upper end of the tubing with its opposite end exposed to the pressure of the well liquid in the casing so as to be operable by a predetermined differential in such pressures.

2. A well flowing apparatus including, a well casing having a well liquid inlet, a well tubing extending through the well casing and having its lower portion communicating with the bore of the casing, a support connected in the tubing string, a flow valve assembly arranged to be run into and removed from the well tubing and adapted to be removably supported on said support, means for introducing a pressure lifting gas into the upper end of the tubing so that the same flows downwardly therein, the valve assembly including a valve plunger located in the line of flow through the tubing for controlling the admittance of said gas to the liquid in the casing and having one end exposed to the gas in the upper end of the tubing with its opposite end exposed to the pressure of the well liquid in the casing so as to be operable by a predetermined differential in such pressures, and means on one extremity of the valve plunger for metering the volume of gas flowing past said plunger when the same is in an open position.

3. A well flowing apparatus including, a well casing having a well liquid inlet, a well tubing extending through the well casing and having its lower portion communicating with the bore of the casing, a support connected in the tubing string, a flow valve assembly arranged to be run into and removed from the well tubing and adapted to be removably supported on said support, means for introducing a pressure lifting gas into the upper end of the tubing so that the same flows downwardly therein, the valve assembly including a valve plunger located in the line of flow through the tubing for controlling the admittance of said gas to the liquid in the casing and having one end exposed to the gas in the upper end of the tubing with its opposite end exposed to the pressure of the well liquid in the casing so as to be operable by a predetermined differential in such pressures, means on one extremity of the valve plunger for metering the volume of gas flowing past said plunger when the same is in an open position.

same is in an open position, and means formed in the surface of the plunger for further metering said flow as the plunger is moved toward a closed position.

5. A well flowing apparatus including, a well casing having a well liquid inlet, a well tubing extending through the well casing and having its lower portion communicating with the bore of the casing, a support connected in the tubing string, a flow valve assembly arranged to be run into and removed from the well tubing and adapted to be removably supported on said support, and means for introducing a pressure lifting gas into the upper end of the tubing so that the same flows downwardly therein, the valve assembly including a valve plunger located in the line of flow through the tubing for controlling the admittance of said gas to the liquid in the casing and having one end exposed to the gas in the upper end of the tubing with its opposite end exposed to the pressure of the well liquid in the casing so as to be operable by a predetermined differential in such pressures, said plunger having a plurality of channels in its surface through which the admitted gas flows, said channels being constructed to automatically meter the flow as the plunger moves toward a closed position.

5. As a sub-combination in a well flowing apparatus, a flow device including a cylinder having a portion of its bore reduced in diameter, a valve seat in the cylinder and a valve plunger having a sliding fit in said reduced portion of the bore and having a length greater than the length of such portion, said plunger having channels in its surface for permitting a flow past the plunger, said channels coacting with the reduced portion of the bore to completely close flow past the plunger, the extremities of said channels being gradually reduced whereby as said channels move into the bore toward a completely closed position, the flow through said channels is gradually reduced and metered, a tapered metering element on one end of the plunger, and a valve head on the opposite end of said plunger, the latter having by-passes therein for permitting a substantially unrestricted flow past the head when the same is in an unseated position.

50. 6. A well flowing device for raising well fluids from a well including, a pair of conduits in said well, said conduits having their lower ends communicating with each other and one of said conduits having a well liquid inlet whereby the well liquids may rise upwardly therein and may also rise upwardly in the lower portion of the other conduit, a flow valve assembly adapted to be lowered through the bore of the latter conduit and removably supported therein, said assembly including a valve element and seat for closing the bore of the conduit within which the assembly is supported, said valve element being located in the line of flow through the conduit whereby opposite ends thereof are exposed to the pressures on opposite sides of the assembly, and means for introducing a lifting fluid into the conduit above the valve assembly, whereby the valve element is exposed on one side to the lifting fluid pressure and on its opposite side to the well liquid pressure so as to be actuated thereby to control the flow of lifting fluid to the well liquid conduit.

7. A well flowing device including, a well liquid flow line, a well tubing having its lower end communicating with the flow line, an elongate sup-

porting nipple connected in the well tubing and having an internal tapered seating surface, a flow valve assembly adapted to be lowered through the tubing and removably supported on said seating surface, the assembly including a tubular housing having a valve seat therein, a spring pressed valve member for controlling flow through said housing to control flow through the tubing, said valve member being located in the line of flow through the conduit in which the assembly is mounted, whereby opposite ends of said member are exposed to the pressures on opposite sides of said assembly, and means for introducing a lifting fluid into the tubing above the assembly, whereby the pressure of said lifting fluid holds the assembly on the seat and also acts against one side of the member to urge the same toward a closed position.

8. A well flowing device including, a well liquid flow line, a well tubing having its lower end communicating with the flow line, an elongate supporting nipple connected in the well tubing and having an internal tapered seating surface, a flow valve assembly adapted to be lowered through the tubing and removably supported on said seating surface, the assembly including a tubular housing having a valve seat therein, a spring pressed valve member for controlling flow through said housing to control flow through the tubing, said valve member being located in the line of flow through the conduit in which the assembly is mounted, whereby opposite ends of said member are exposed to the pressures on opposite sides of said assembly, means for introducing a lifting fluid into the tubing above the assembly, whereby the pressure of said lifting fluid holds the assembly on the seat and also acts against one side of the member to urge the same toward a closed position, and pressure seal packing means interposed between the assembly and the bore of the nipple and acted upon by the lifting fluid pressure to pack off around said assembly.

9. A well blowing device including, a well liquid flow line, a well tubing having its lower end communicating with the flow line, an elongate supporting nipple connected in the well tubing and having an internal tapered seating surface, a flow valve assembly adapted to be lowered through the tubing and removably supported on said seating surface, the assembly including a tubular housing having a valve seat therein, a spring pressed valve member for controlling flow through said housing to control flow through the tubing, said valve member being located in the line of flow through the conduit in which the assembly is mounted, whereby opposite ends of said member are exposed to the pressures on opposite sides of said assembly, and means for introducing a lifting fluid into the tubing above the assembly, whereby the pressure of said lifting fluid holds the assembly on the seat and also acts against one side of the member to urge the same toward a closed position, the valve member having a plurality of vertical channels in its external surface, said channels being reduced toward their ends to meter the flow of fluid passing the member when the same is in an open position.

10. The combination with a flow conduit having its lower end communicating with a well liquid flow line, of a flow valve assembly including a housing adapted to be lowered through the conduit and removably seated therein, said housing having a bore communicating with the

bore of the conduit, a movable valve element located in the line of flow through the conduit for closing the bore of the housing and having its lower end exposed to the pressure in the liquid flow line and its upper end exposed to pressure in the conduit thereabove, and means for introducing a pressure lifting into the upper end of the conduit, whereby the valve element is actuated by the pressure differential thereacross to admit the lifting fluid to the flow line, the lifting fluid pressure also acting downwardly on the assembly to hold the same in its seated position within the conduit.

11. The combination with a flow conduit having its lower end communicating with a well liquid flow line, of a flow valve assembly including a housing adapted to be lowered through the conduit and removably seated therein, said housing having a bore communicating with the bore of the conduit, a movable valve element located in the line of flow through the conduit for closing the bore of the housing and having its lower end exposed to the pressure in the liquid flow line and its upper end exposed to pressure in the conduit thereabove, means for introducing a pressure lifting into the upper end of the conduit, whereby the valve element is actuated by the pressure differential thereacross to admit the lifting fluid to the flow line, the lifting fluid pressure also acting downwardly on the assembly to hold the same in its seated position within the conduit, the valve element having a longitudinal channel in its external surface which channel is gradually reduced in area toward the extremity of the element to meter the flow of fluid past the element when the same is in an open position.

12. A well flowing device including, a well tubing, a flow line communicating with the lower end of the tubing, a support connected in said tubing and having an internal seat, a flow valve assembly adapted to be run into the well through the bore of the tubing and arranged to engage the seat so as to be removably supported in the tubing bore, the assembly having a flow passage which communicates with the tubing bore, means having opposite ends exposed to the pressures on opposite sides of the passage within the passage operable by the pressure differential thereacross for controlling the flow therethrough, and means for introducing a lifting gas into the upper end of the tubing, whereby the flow of said gas downwardly through the tubing and into the flow line is controlled by the valve assembly.

13. A well flowing device including, a well tubing, a flow line communicating with the lower end of the tubing, a support connected in said tubing and having an internal seat, a flow valve assembly adapted to be run through the bore of the tubing and arranged to engage said seat so as to be supported thereby, means for sealing off the space between the assembly and tubing bore when the former is in position therein, means within the assembly having opposite sides exposed to the tubing and flow line pressures and operable by the differential in such pressures for controlling the flow through the assembly, and means for introducing a lifting gas into the upper end of the tubing, whereby the flow of said gas downwardly through the tubing and to the flow line is controlled by the valve assembly.

14. A well flowing apparatus including, a well casing having a well liquid inlet, a well tubing extending through the well casing and having its lower portion communicating with the bore of the casing, a support connected in the tubing

string above the point of communication between the tubing and casing, a flow valve assembly arranged to be run into and removed from the well tubing and adapted to be removably supported on said support, said assembly including a valve seat and valve member adapted to engage the seat to close the flow through the assembly and through the tubing, said valve member having one end exposed to the pressure in the tubing above the assembly with its other end exposed to the pressure in the tubing below the assembly, whereby the valve member is actuated by the differential in such pressures, and means for introducing a lifting gas into the upper end of the tubing, whereby the valve means controls the admittance of said gas to the lower portion of the tubing and then to the well liquid in the casing.

15. A well flowing apparatus including, a well casing having a well liquid inlet, a well tubing extending through the well casing and having its lower portion communicating with the bore

5 of the casing, a support connected in the tubing string, a flow valve assembly arranged to be run into and removed from the well tubing and adapted to be removably supported on said support, said assembly including a valve element located in the line of flow through the tubing for closing the bore of the tubing, said element having one side exposed to the pressure of the tubing above the assembly and its other side exposed to the pressure in the casing, whereby it is actuated by the differential in such pressures, means for introducing a lifting gas into the upper end of the tubing, whereby the valve means controls the admittance of said gas to the lower portion of the tubing and to the well liquid in the casing, and pressure seal packing means exposed to the gas pressure in the tubing above the valve assembly for packing off between said assembly and said support.
